UNITED STATES PATENT OFFICE.

FREDERICK H. KOLBE, OF DETROIT, MICHIGAN, ASSIGNOR TO KELVINATOR CORPORATION, OF DETROIT, MICHIGAN, A CORPORATION OF DELAWARE.

REFRIGERATING APPARATUS.

1,418,806.

Specification of Letters Patent. Patented June 6, 1922.

Application filed July 29, 1920. Serial No. 399,656.

To all whom it may concern:

Be it known that I, FREDERICK H. KOLBE, a citizen of the United States, residing at Detroit, in the county of Wayne and State of Michigan, have invented a certain new and useful Improvement in Refrigerating Apparatus, of which the following is a full, clear, and exact description, reference being had to the accompanying drawings.

- 10 This invention relates to mechanical refrigerating apparatus and especially to that of the domestic type which is required to be operated with a minimum of supervision or attention, although it is not restricted to such use. In the patent of Heideman and Hadjisky, issued January 27, 1920, No. 1,329,350, there was described and claimed a means and method of regulating an automatic mechanical refrigerator, comprising an expansion coil having its terminal turns uppermost and a thermostat supported in such wise as to be subject to the temperature conditions in such terminal turns. According to the specific construction set forth in that patent the thermostat was itself supported in direct contact with the entering air although the patent was not restricted to that arrangement. I have discovered that the operation is further improved in case the thermostat is so supported as to be subject to the temperature conditions in the terminal turns but shielded from direct contact with the convection currents; the effect of this arrangement being to produce a mechanical refrigerating device in which a sufficiently low temperature shall be maintained with a smaller total time of compressor operation and hence with a saving of energy; while further objects and advantages of the invention will become apparent as the description proceeds. This present construction constitutes a specific improvement upon the former patent, subject to the same broad claims and differing in the particular noted.
- 15 In the drawings accompanying and forming a part of this application I have illustrated certain physical forms in which my inventive idea may be embodied although it will be understood that these drawings are intended to be illustrative only and not to limit me to the particular details therein shown. In these drawings Fig. 1 illustrates my improved expansion coil and thermostat located in a refrigerator and operatively connected to the other elements of the refrig-

erating system; Fig. 2 is a vertical sectional view of the thermostat and associated parts drawn to an enlarged scale; and Fig. 3 illustrates a modified form of device.

Referring first to Figs. 1 and 2, I have for purposes of illustration shown a corner of an ordinary domestic refrigerator having a brine tank and cooling coil located in the chamber ordinarily provided for ice. This refrigerator comprises an external rectangular casing 1 having therein an upright partition 2 spaced from the top as shown to provide an air passage 3 and also spaced from the bottom (not shown) to provide another passage in a well known manner. The chamber 4 defined at one side of the partition is employed for the storage of food and the chamber 5 at the other side of said partition constitutes a refrigerant space, the upper part whereof is ordinarily employed for ice which is supported in such wise that the circulating air can pass over and around the same.

In this ice space I have shown a metal brine tank 6 having therein a submerged pipe coil 7 whose terminal turns are continued above the tank and formed into a closely wound upright coil 8, the turns of which are in heat conducting relation with each other and with the tank top, and smaller in diameter than the tank 6. In the present embodiment I have shown this coil as consisting of two layers of piping, but do not limit myself thereto. The initial end of the coil 7 is connected to an expansion valve 10 which in turn communicates with the condenser 11; the outlet end of the coil 8 communicates with the intake 12 of a compressor 13 whose pressure side is connected to said condenser. The compressor is driven by the electric motor 14, whose operation is controlled by the thermostat located inside the coil 8. So far as this application is concerned the essential feature of the thermostat is a heat responsive body 16 located inside the coil 8 and having a cap 17 resting snugly upon the top of said coil so as to prevent the entrance of any material amount of convection currents. In the present embodiment the heat-responsive body consists of an expandible vessel filled with liquid of low boiling point, but any suitable device could be employed; and the cap constitutes a support for such member and is formed with 110

an inclined seating portion 18 conforming closely to the configuration of the coil, but this particular feature is not essential. Also the winding of the coil in a plurality of layers is not essential, although practically convenient from a manufacturing stand-point and also affording increased heat conduction for a purpose which will appear later.

- 10   10   Mounted on the cap 17 is a switch box 20 having suitable switch mechanism 21 therein mechanically connected to the vessel 16 in operating relation, the terminals of the switch being connected with the positive and negative leads 23 and 24 connected in series with the motor 14 and a suitable source of electricity, not shown.

In Fig. 3 I have shown a slightly modified construction wherein the brine tank is shown 20 at 6^a, and the coil 7^a rises uninterrupted from the bottom of the tank and through the top thereof in a single geometrical figure, the portion of the coil next above the top of the tank occurring in the form of 25 spaced turns 7^b so that the air currents may obtain intimate contact therewith and have access to all sides of the tank. The uppermost end of this coil, however, has its turns closely laid together as shown at 8^a and forming a seat having a suitable thermostat 15^a. The expansion valve 10^a is as before connected to the initial turn of the expansion coil and the return pipe 12^a to the topmost turn of the expansion coil.

- 30   35   With the constructions herein set forth it will be seen that the initial turns of the expansion coil are submerged in a brine tank so that the first effect of the refrigerant is to cool the latter to a very low temperature; while the abstraction of heat from the brine will prevent any such cooling of the terminal turns as to actuate the thermostat until after the brine has become very thoroughly cooled, inasmuch as these turns 40 lie in the path of the entering convection currents so as to be kept warmed thereby until the last possible moment; however, as soon as the frost line reaches this point a sudden change of temperature is produced 45 which causes a positive and quick operation of the thermostat causing the stopping of the motor. During the idle period the refrigeration is maintained by the action of the brine tank which absorbs heat slowly 50 because of the large mass and high specific-heat-capacity of its contents. As soon as the thermostat has become sufficiently heated by the incoming air, the motor will be restarted and the refrigerating action repeated, 55 but by shielding the thermostat from the entering air this action is delayed until the warming effect had had an opportunity to be transmitted inwardly to it through the pipe coil 8; and this action is the more de- 60 lay by reason of the close thermal contact 65

of the turns of the terminal coil with each other and with the top of the tank which prevents any such heating of the same as to actuate the thermostat until the brine has become warmed to a considerable degree. 70 It will be noted that the refrigerant coil will be cooled from the bottom upward inasmuch as the cooling fluid enters the coil from below and passes through the brine tank. To assist this action the coils are preferably 75 dipped in molten zinc or tin so as to bind them closely together in heat-conducting relation and are preferably soldered directly to the top of the tank as shown in Fig. 2.

It will be understood that many changes 80 in detail and construction and arrangement can be made within the scope of my invention and that I do not limit myself to the particular features herein shown except as the same are specifically recited in the annexed claims.

Having thus described my invention, what I claim is:

1. In a refrigerating device, a storage chamber and a refrigerating chamber having air circulation openings, an upright refrigerant coil in said chamber and cooled from below upwardly, the uppermost turns of said coil being located nearest to the air-inflow opening and in the direct air stream 95 therefrom, a thermostatic device located inside the uppermost turns of said coil, and a cap preventing entrance of air into the end of said coil.

2. In a refrigerating device, an upright 100 refrigerant coil having its uppermost turns close together, a thermostatic device depending into said turns, a cap covering the top of said coil, and an electric switch operatively connected to said device.

3. In a refrigerating device, in combination, a brine tank, a refrigerating coil therein and rising above the same, said coil terminating at the top in a closely convoluted vertical portion of smaller diameter 110 than said tank, a heat responsive device inside the top of said coil, an electric switch operatively connected to said device, and a cap covering said vessel and the top of said coil.

4. In a refrigerating device, in combination, a brine tank, a refrigerating coil therein and rising above the same, the portion of said coil which projects above said tank being formed with its turns in contiguous, heat-conducting relation with each other and with the tank top, a thermostatic device located inside said coil, means forcing refrigerant into the opposite end of said coil, and means for preventing the entrance 120 of convection currents into such terminal turns.

5. In a refrigerating device, a storage chamber and a refrigerating chamber having air circulating openings, an upright 125

- refrigerant coil in said chamber and having its uppermost turns contiguous with each other, a brine tank surrounding the lowermost turns of said coil, the uppermost turns being located nearest the air inlet opening and in the direct air stream therefrom, a compressor operatively connected through a condenser with the lowermost turns of said coil, a thermostatic device located inside such uppermost turns and operatively connected to said compressor, and means preventing entrance of convection currents into such uppermost turns.
- 5 6. In a refrigerating device, in combination, a brine tank, an expansion coil partly immersed therein and partly rising above the same, the portion of said coil which rises above said tank being formed with its turns in contiguous heat conducting relation with each other and in a plurality of layers, 20 means for supplying liquid refrigerant to the lower turns of said coil and withdrawing vaporized refrigerant from the upper turns thereof and a thermostatic device located inside said upper turns and adapted 25 to control the operation of said means.
- In testimony whereof, I hereunto affix my signature.

FREDERICK H. KOLBE.
